UNITED STATES PATENT OFFICE.

GEORGES AUGUSTIN SALINS, OF VINCENNES, FRANCE, ASSIGNOR TO PATHÉ CINÉMA,
ANCIENS ÉTABLISSEMENTS PATHÉ FRERES, OF PARIS, FRANCE.

MACHINE FOR THE AUTOMATIC COLORING OF FILMS.

Application filed July 15, 1924, Serial No. 726,112, and in France July 21, 1923.

In the known machines for coloring cinematographic films wherein the color is applied by means of rollers, it is necessary when changing from one color to another to stop the motion of the film or to insert a connecting band between the two parts which are to have different colors.

The present invention relates to an apparatus for the continuous coloring of the different parts of a film according to the color which is to be given to each part without reducing the speed of travel of the film this being performed by means of suitable coloring rollers whereof each is arranged for applying one color and the whole set of rollers is placed in series, the said rollers being automatically moved towards or from the film at the proper time by the action of the film itself or by like means.

20 In the accompanying drawings showing by way of example an embodiment of the invention:

Fig. 1 is an elevational view of a portion of the apparatus, the contact wheels being shown in section and the coloring drums in elevation.

Fig. 2 is a corresponding plan view.

Fig. 3 is a side view of a contact wheel, with certain parts removed in the lower part of the figure.

Fig. 4 is a plan view of two consecutive coloring elements with their clutching mechanism, partly in section.

Fig. 5 is an elevational view of the clutching mechanism at the time of cessation of the control.

Fig. 6 is a view showing the resumption of the control.

Fig. 7 is an elevational view of the coloring mechanism in the operative position, and

Fig. 8 is a like view in the inoperative position.

Fig. 9 is a section on the line 9—9 of Fig. 8, and

Fig. 10 a section on the line 10—10 of the same figure.

Fig. 11 is a side view corresponding to Fig. 7.

Fig. 12 is a diagrammatic view showing the perforations in the film for the automatic control of the coloring means.

Fig. 13 is a like view showing the arrangement of the pointed members and the connections on the contact wheels.

Fig. 14 is a diagram of the circuit for a series of elements of a contact wheel.

In the present example, the machine comprises an upper horizontal shaft 1 which is rotated in a continuous manner by suitable means and to which are keyed the wheels a^1 , a^2 , a^3 carrying the film to be colored f and provided with the entraining teeth 3. The number of the said wheels corresponds to the number of colors to be employed for coloring the film, for example eight colors. Below the said wheels are disposed the guiding wheels b^1 , b^2 , b^3 , or coloring drums, which have a smooth periphery and are in the inclined position, as shown in Fig. 2. The film arriving for instance upon the wheel a^4 passes below the wheel b^4 , mounts upon the wheel a^3 , descends again below the wheel b^3 , and so on. The lower wheels b^1 , b^2 etc. are loose on the shaft, and are mounted in bearings. The tension of the film can be ensured by any suitable means.

Below each coloring wheel or drum b^1 , b^2 etc., is disposed a coloring device. Each of the said devices, which corresponds to a given color, comprises a coloring roller 13 (Fig. 11) with smooth periphery which is partially immersed in a small trough 14, Fig. 7, containing the color. The said coloring roller is mounted on the end of a lever 15 which is pivoted at the middle upon the axle 16 and has at the other end a stud 17 which is urged against the cam 18 by the spring 19. The shaft 20 of the coloring roller 13 has mounted thereon a controlling disc 21.

Upon the shaft 16 is pivoted the lever 22 upon whose other end are mounted a disc 23, Fig. 10, and a pulley 24, which are connected together by the small shaft 25. The pulley 24 is constantly actuated by the double pulley 26, through the medium of the belt 27, whilst the pulley 26 is constantly actuated by a shaft, not shown, which is common to all the elements. The lever 22 is urged against a stop-piece 28 by the spring 29.

When the cam 18 is in the position shown in Fig. 8, the coloring roller is separated from the film, and it ceases to rotate; the disc 21 is out of contact with the disc 23; in these conditions, the film is not colored when passing through the said element. But if the cam makes half a revolution in the direction of the arrow, the boss 30 which

comes into position in the first place will bring the coloring roller 13 very close to the film, and then the said roller will move back by a short distance and will be held in this 5 position, Fig. 7, by the part 31 of the cam. Since the distance between the control discs 21 and 23 is less than the distance between the coloring roller and the film, Fig. 8, the latter roller will rotate before attaining the 10 film, and the coloring will begin at the exact moment determined by the said boss.

The coloring matter is placed upon the film by capillarity, the coloring roller being separated from the film by one of two 15 millimetres according to the consistency of the color; the boss 30 serves to start the capillary action. When the cam 8 again makes half a revolution, the coloring action ceases, and the apparatus is now in the 20 position shown in Fig. 8.

The releasing device allowing the cam to make half a revolution comprises (Fig. 4) a shaft 41 which is in continuous rotation in the bearing 42 and carries at the ends a pulley 25 43 and a ratchet wheel 44; a cam 45 is secured to the said bearing. In another bearing 46 is rotatable a shaft 47 having upon one end, and adjacent the ratchet 44, a disc 48 to which is pivoted at 49' a pawl 49 which 30 the spring 50 tends to separate from the ratchet teeth; a stud 51 secured to the said ratchet is caused to bear upon the periphery of the cam 45 under the pressure of the spring 50. The cam 45 has formed therein 35 the cut-out portion 45', and when the stud 51 of the ratchet drops into the said cut-out portion, the pawl will pivot about and will be released from the said ratchet, so that the disc 48 will come to a stop after having made 40 exactly one revolution. Fig. 5 shows the said pawl in the raised position. At the other end of the shaft 47 is mounted a bevel gear 52 engaging a like gear 54^a mounted on the shaft 54^b of a pinion 54, Figs. 7 and 8. 45 The latter pinion engages a pinion 55 which has twice the diameter of the former and is secured to the cam 18; so that each revolution of the disc 48 will correspond to half a revolution of the cam 18. The said pawl 50 is lowered into engagement with the ratchet by a lever 56 which is attracted by the electro-magnet 57 at the proper time.

In the apparatus herein represented, the film to be colored is utilized to operate the 55 electro-magnets 57 and hence the corresponding coloring rollers 13. For this purpose, in the present example, the film is provided with perforations at suitable points upon its length; these may be disposed as shown in 60 Fig. 12, in the case of an apparatus for eight colors.

It is observed in this figure that the perforations $m' n' o' \dots t'$ are situated upon a common longitudinal line α . The perforations $m q, n r, o s, p t$ are situated respec-

tively upon the lines A, B, C, D. The perforations m, m' are situated upon a common line F G separating two images. The same prevails for $n n', o o', p p'$. The perforations $q q'$ are respectively below and above 70 a given image, and the same is true for the perforations $r r', s s', t t'$. Each pair of perforations corresponds to a given color.

The film to be colored acts by the said perforations upon the contact elements 75 disposed in the entraining wheels a^1, a^2 etc. so as to control the solenoids 57 and hence the coloring rollers.

In the present example, the wheels a^1, a^2 etc. which are of ebonite or other insulating 80 substance have for instance a circumferential length corresponding to twenty images, and are provided with twenty radial slots 60, Fig. 3. In each slot are disposed two levers 68, 68' made of ebonite or like insulation, 85 each lever having at the end a pointed member 69, 69' respectively, these being adapted to enter the respective perforations m, m', n, n' of the film. The circumferential distance between two adjacent pointed members 90 corresponds to the height of an image. Each of the levers 68 disposed in the left hand side of each wheel (Fig. 1) is riveted to a metallic lever 70 pivoting on an axle 71 and provided with a metallic contact arm 72 upwardly urged by the spring 73 in order to make contact with a spring strip 77 mounted in a lateral recess in the said wheel. The twenty springs 73 situated on the same side of the wheel are secured to a sleeve 74 adapted 100 to come into contact with a stationary cam 75 which is insulated from the shaft 1 and carries a terminal 76 connected to one pole of the corresponding electro-magnet 57. As above stated, an electro-magnet is provided 105 for each of the wheels a^1, a^2, a^3 etc.

In normal operation, the levers 70 tend to swing to the right, Fig. 1, when urged by the springs 73, but they come into contact with the stationary cam 75, which has 110 a suitable cut-out portion, in such manner that when a lever 70 comes opposite the said cut-out portion, its pointed member 69 will come into contact with the film (wheels a^2, a^3, a^4 , Fig. 1) and can enter one of the 115 perforations $m, n, o, \dots t$ when the latter comes into the proper position (wheel a^1 , Fig. 1). The lever 70 will now swing about under the action of the spring 73, and the arm 72 comes into contact with the spring 77. The pointed member 69 is withdrawn 120 from the perforation of the film before this latter leaves the wheel, due to the action of the cam 75 which impels the lever 70 to the left, Fig. 1, after the contact has been made 125 between the arm 72 and the spring 77, as above stated.

In the right-hand portion of each wheel, Fig. 1, are disposed the elements 70', 71', 72', 73', etc., corresponding to the respective 130

elements 70, 71, 72, 73, etc., above described. In the present example, the cut-out portion of each cam 75 is situated opposite a cut-out portion of the cam 75', in the first four wheels (a^1 to a^4), and it is separated from the cut-out portion of the cam 75' by an angle corresponding (on the circumference) to the height of an image, in the other four wheels (a^5 to a^8).

10 Fig. 14 shows the electric circuit for each wheel a^1 , a^2 , a^3 , etc., the said circuit comprising a terminal 76', a battery 80, the corresponding electro-magnet 57, and the second terminal 76. The said circuit is closed when the two arms 72, 72' come into contact at the same time with the respective springs 77, 77', the two springs being connected by suitable connecting means 81 whose disposition will be further considered.

15 The levers 68 have in each case a length such that the pointed members 69' of each wheel shall be situated upon a circumference corresponding to the line X, Figs. 12 and 13. We have represented in a diagrammatic manner, various superposed views showing partial developments of the first, fifth and eighth wheel, said wheels being designated by a^1 , a^5 , a^8 ; in this figure, 69 and 69' indicate the position of the pointed members 20 relative to each slot 60; 77, 77' representing the two springs above mentioned, and 81 their connection. It is observed in this figure that the springs 77, 77', which are connected together in each wheel, correspond to the pointed members 69, 69' which have determined positions, these positions corresponding respectively to the position of two perforations of the film. For example, the pointed members 69, 69' of the 25 fifth wheel (a^5), corresponding to the contact springs 77, 77' connected together by the connecting means 81, are situated upon the lines A and X and cooperate with the perforations q q' of the film. The pointed members of the eighth wheel (a^8) cooperate with the perforations t t' , etc.

The operation is as follows:

Let it be supposed that a certain length of the film is to be colored in blue, and 30 that the coloring operation is to be controlled by the wheel a^5 ; in this event, the film is provided with the two perforations q and q' at a suitable point upon its length, so that when these perforations are engaged 35 with the respective pointed members 69, 69' of the wheel a^5 , the first image to be colored in blue will come opposite the blue-coloring roller. At this time, the circuit of the electro-magnet corresponding to the 40 said roller will be closed; the lever 56 will be attracted (Fig. 5); the pawl 49 now engages the ratchet 44 and is drawn forward by the same, together with the disc 48 which will make one revolution under the action 45 of the above-mentioned control. The cam

18 will thus make half a revolution and will assume the position shown in Fig. 7. The corresponding coloring roller 13 will thus deposit blue color upon the film until it becomes separated therefrom. To effect this 50 separation, the film comprises at a suitable point upon its length two perforations which are analogous to q q' . These two perforations serve to effect the rotation of the cam 18 by another half-revolution, thus 55 bringing the coloring roller into its inoperative position, in which it will remain until a new series of perforations q q' come into action.

A like operation takes place for each of 60 the said coloring rollers.

Obviously, the said invention is not limited to the hereinbefore described form of construction. In particular, the contact wheels a^1 , a^2 , a^3 , instead of being placed side by 65 side, may be disposed in the same plane or may be otherwise situated, and like conditions may prevail for the lower wheels b^1 , b^2 , b^3 , etc.

The ratchet device controlling the cams 90 18 may be replaced by a like clutching device.

The automatic motion of the said rollers, instead of being controlled by the perforations in the film, may be controlled by 95 notches, metallic contacts, or the like, which need not to be located upon the lines of separation of the images. It may also be controlled by any suitable auxiliary element such as a band, perforated pasteboard, toothed cylinder, counter, and the like.

The coloring matter may consist of animal or like color, dissolved in water, alcohol, ether, in gelatinous solution, or incorporated with any suitable varnish having as a 100 basis celluloid, acetate or cellulose, gum arabic or the like, and it can be applied to the backing of the film or to the gelatine side.

In an apparatus employing colored gelatine, the trough 14 is so disposed that the gelatine shall be maintained in the liquid state, as in the known apparatus for applying gelatine or emulsion, and at each revolution the film is preferably caused to pass through a sheath in which a sufficiently low 110 temperature is maintained in order that the gelatine applied to the film shall be rapidly dried.

Having now described my invention what I claim as new and desire to secure by Letter Patent is:

1. In a machine for coloring films, several mechanisms each comprising a coloring roller corresponding to a determined color, a movable support for said roller and means travelling in synchronism with the film to be colored and adapted to control the movement of said support and to move said roller towards and from the said firm.

2. In a machine for coloring films, several

- mechanisms each comprising a coloring roller corresponding to a determined color, a pivoting lever carrying said roller, a cam for actuating said lever, and means travelling in synchronism with the film to be colored for controlling the intermittent rotation of said cam whereby said roller is moved towards and from the film to be colored.
- 10 3. In a machine for coloring films, several mechanisms each comprising a coloring roller corresponding to a determined color, a pivoting lever carrying said roller, a cam for actuating said lever, driving means a clutch for intermittently connecting said cam to said driving means, and means travelling in synchronism with the film to be colored for controlling said clutch whereby said roller is moved towards and from the said film.
- 15 4. In a machine for coloring films, a film to be colored provided with perforations formed at determined places thereof, several mechanisms each comprising a coloring roller corresponding to a determined color, a pivoting lever carrying said roller, a cam for actuating said lever, driving means, a clutch for intermittently connecting said cam to said driving means, and means controlled by the said perforations of the film for controlling the said clutch whereby said roller is moved towards and from the film to be colored.
- 20 5. In a machine for coloring films, a film to be colored provided with perforations formed at determined places thereof, several mechanisms each comprising a coloring roller corresponding to a determined color, a pivoting lever carrying said roller, a cam for actuating said lever whereby said roller is moved towards and from the said film, driving means, an electro-magnetic clutch for intermittently connecting said cam to said driving means, an electric circuit for actuating said clutch, and switches in said circuit controlled by said perforations in the said film.
- 25 6. In a machine for coloring films, a film to be colored provided with perforations formed at determined places thereof, several mechanisms each comprising a coloring roller corresponding to a determined color, a pivoting lever carrying said roller, a cam for actuating said lever so as to move said roller towards said film and maintain the same at a short distance from said film whereby the color is transferred from the roller to the film by capillarity and to move said roller from the film, driving means, an electro-magnetic clutch for intermittently connecting said cam to said driving means, an electric circuit for controlling said clutch, and switches in said circuit controlled by said perforations in said film.
- 30 7. In a machine for coloring film, a film to be colored, several mechanisms each comprising a coloring roller corresponding to a determined color, a pivoting lever carrying said coloring roller, a cam for actuating said lever so to move said coloring roller towards and from said film, an actuating friction roller rigidly connected to said coloring roller, a control friction roller adapted to cooperate with said actuating friction roller, a pivoting arm carrying said control friction roller, means for rotating said actuating friction roller, a boss on said cam between the upper and lower portion of the cam-profile for pressing a short time the coloring roller against the said film whereby positively starting the coloring operation, and means travelling in synchronism with the said film for controlling the intermittent rotation of said cam.
- 35 8. In a machine for coloring films, a film to be colored, several mechanisms each comprising a coloring roller corresponding to a determined color, a pivoting lever carrying said roller, a cam for actuating said lever so as to move said roller towards and from said film, a rotatable disc, a pawl pivoted on said disc, a ratchet wheel cooperating with said pawl, means for operatively connecting said disc to said cam, means for continuously rotating said ratchet wheel, yielding means for constantly urging said pawl out of engagement with said ratchet wheel, a lever adapted to engage said pawl with said ratchet wheel, an electro-magnet for controlling said lever, a stationary cam cooperating with said pawl for allowing the same to disengage from said ratchet wheel at a determined point of each revolution of said disc, an electric circuit for energizing said electro-magnet, switches for closing and opening said circuit and means travelling in synchronism with the said film for controlling said switches.
- 40 9. In a machine for coloring films, a film to be colored provided with perforations formed at determined places thereof, several mechanisms each comprising a coloring roller corresponding to a determined color, an oscillating lever carrying said roller, a cam for actuating said lever whereby said roller is moved towards and from the said film, driving means, an electro-magnetic clutch for intermittently connecting said cam to said driving means, an electric circuit for actuating said clutch, an entraining wheel for the film, switches carried by said wheel, said switches being branched in the said circuit, pivoting levers on said wheel for controlling said switches respectively, and studs on said pivoting levers adapted to enter the perforations of the film whereby closing the respective switches.
- 45 10. In a machine for coloring films, a film to be colored provided with perforations disposed in longitudinal rows and between the images of the film, several mechanisms each

- comprising a coloring roller corresponding to a determined color, an oscillating lever carrying said roller, a cam for actuating said oscillating lever, driving means, an electro-magnetic clutch for intermittently connecting said cam to said driving means, an electric circuit for actuating said clutch, an entraining wheel for the film, switches carried by said wheel, said switches forming as many groups of each two series-connected switches as the circumferential length of the wheel comprises the length of one image of the film, each of said groups of switches being branched in said circuit, pivoting levers on said wheel for controlling said switches respectively, each pivoting lever carrying a stud adapted to enter the perforations of one of said rows whereby closing the corresponding switch. 5
- 10 11. In a machine for coloring films, a film to be colored provided with perforations disposed in longitudinal rows and between the images of the film, several mechanisms, each comprising a coloring roller corresponding to a determined color, an oscillating lever carrying said roller, a cam for actuating said lever whereby said roller is moved towards and from the said film, driving means, an electro-magnetic clutch for intermittently connecting said cam to said driving means, an electric circuit for actuating said clutch, an entraining wheel for the film, switches carried by said wheel and forming as many groups of each two series-connected switches as the circumferential length of the wheel comprises the length of one image of the film, each of said groups of switches being branched in said circuit, pivoting levers disposed on either side of the 15 20 25 30 35 40 45 50 55 60 65 70 75
- wheel in radial slots of the latter, each pivoting lever being adapted to control one switch and carrying a stud adapted to enter the perforations of the film, coming in coincidence therewith, stationary cams disposed respectively on either side of said wheel and cooperating with said levers to allow penetration of said studs into said perforations during a determined part of a revolution of said wheel whereby closing the corresponding switches. 50
12. In a machine for coloring films, a film to be colored provided with perforations disposed in longitudinal rows and between the images of the film, several mechanisms each comprising a coloring roller, electromagnetic means for moving said roller towards and from the film, an electric circuit for actuating said electro-magnetic means, an entraining wheel for said film, switches carried by said wheel and forming as many groups of each two series-connected switches as the circumferential length of the wheel comprises the length of one image of the film, each of said groups of switches being branched in said circuit, pivoting levers on either side of said wheel in radial slots of the latter, each pivoting lever being adapted to control one switch and carrying a stud adapted to enter the perforations of one of said rows, stationary cams disposed on either side of said wheel and cooperating with said levers to allow penetration of said studs into said perforations during a determined part of a revolution of the wheel whereby closing the corresponding switches. 60 65 70 75

In testimony whereof I have signed my name to this specification.

GEORGES AUGUSTIN SALINS.
